UNITED STATES PATENT OFFICE.

ARTHUR W. THOMPSON, OF OTTAWA, ONTARIO, CANADA.

OPERATING MECHANISM FOR FUEL-PUMPS OF INTERNAL-COMBUSTION ENGINES.

1,299,062.

Specification of Letters Patent. Patented Apr. 1, 1919.

Application filed June 4, 1918. Serial No. 238,238.

To all whom it may concern:

- Be it known that I, ARTHUR W. THOMPSON, a citizen of the Dominion of Canada, and a resident of the city of Ottawa, Province of Ontario, Dominion of Canada, have invented certain new and useful Improvements in Operating Mechanisms for Fuel-Pumps of Internal-Combustion Engines, of which the following is a specification.
- 10 This invention is an improved operating mechanism for fuel pumps of internal combustion engines of that type in which the necessary quantity of liquid fuel is forcibly injected into the successive compressed air charges to make up the explosive mixture. The injection of the liquid fuel is ordinarily effected by means of a small force pump delivering a fraction of a drop or a few drops of liquid, depending upon the size of the engine, the injection preferably taking place directly into the cylinder, although it may take place into the compressed air charge before the delivery of the latter to the explosion chamber. My invention relates solely 25 to the operating and controlling mechanism for the pump and is particularly adapted for two-cycle engines, although by suitable alteration, it may be adapted to a four-cycle engine.
- 30 Among the important objects of my invention are to operate the fuel pump by means of the compression and rarefaction of the air in the crank case suitably controlled so as to give a quick and forceful injection of the fuel; to automatically or manually time the injection in relation to the compression stroke of the engine piston; and to regulate the amount of fuel injected.
- 35 My improved mechanism includes a free floating air piston forced in one direction by the compression of air in the engine crank case and returned to deliver a pneumatic hammer blow on the fuel pump plunger by the rarefaction of air in the engine crank case. By means of my improved construction I am able to regulate the stroke of this air piston, the time of its return or power-delivering stroke in respect to the engine piston position, and the force of said stroke or blow.
- 40 Various different embodiments of my invention may be readily designed by those skilled in the art. Merely for purposes of illustration and to facilitate a clear understanding of my invention I have illustrated a
- 45 preferred embodiment thereof in the accompanying drawings to which reference is to be had. In these drawings I have illustrated, somewhat conventionally, a two-cycle internal combustion engine but it will of course be understood that such engine forms no portion of my invention and that my invention may be applied to other types of engines and in various different ways and positions.
- 50 In these drawings:
- 55 Figure 1 is a side elevation of an engine provided with my improved fuel pump operating and controlling mechanism, and
- 60 Fig. 2 is a central vertical section through said mechanism on a very much larger scale.
- 65 I have illustrated my invention as applied to a two-cycle engine having a water jacketed cylinder 10 and a crank case 11. The water may be withdrawn from the upper part 70 of the water jacket through a pipe 12, and forced by a pump 13 through a pipe 14 to a cooler 15, from which it may return through a conduit 16 to the water jacket. The pump is shown in the supply from the jacket to the cooler but this is immaterial as the pump 75 may be in the conduit 16 from the cooler to the jacket, or in some cases, a thermo-cycle 80 may be utilized and the pump eliminated or the jacket may be air cooled.
- 85 The air is taken into the crank case 85 through any suitable form of inlet 17, which may have a throttle or other controlling means and an automatic non-return check valve or as shown in the drawing, may be uncovered by the piston at the upper end of 90 its upstroke to permit the inrush of air to the crank case. At the beginning of the downstroke the piston covers port 17 and when near the end of the downstroke it uncovers an exhaust port 21 and finally uncovers 95 a passage 22 connecting the crank case with the working or explosive chamber 23.
- 100 The fuel pump 24 takes liquid fuel from any suitable source of supply and delivers it through a conduit 25 through an injector 26, preferably in the cylinder head. I do not wish to be limited to any particular form of injector but I preferably employ the construction shown in my prior Patent 1,223,124 issued April 17, 1917. This oil pump 24 is 105 of such a size that upon each downstroke of the plunger 27 thereof a sufficient amount of liquid fuel is delivered through the conduit 25 to unite with the air in the chamber 23 and form 110 the explosive mixture. The pump

plunger 27 is normally forced up to its limiting position by a spring 27' until a collar or flange 29 thereon engages with a stop 30, here shown as a bracket, for guiding the 5 pump plunger. As previously stated my invention resides solely in the means for operating this pump plunger at the desired time intervals and to the desired extent to properly deliver the liquid fuel and control the 10 operation of the engine.

In the specific form of my invention illustrated, I employ an air chamber 35 in the form of a cylinder and having a free floating reciprocatory or vibratory member 15 therein in the form of a piston 36. The one end of the cylinder has a passage or conduit 37 connecting it with the interior of the engine crank case so that the portion of the chamber beneath the piston is at all times 20 subject to the gas pressure variations in the crank case. The piston has a rod or striker member 38, suitably guided in the lower cylinder head 39 and substantially in alignment with the pump plunger 27. The upper 25 per cylinder head 40 has a tube or sleeve 41 in alignment with the upper end of the rod 38 and of a size to receive and fit the latter sufficiently closely to prevent any rapid escape of air therebetween when the upper end 30 of the rod is within the tube. This upper end of the rod has a socket in its upper end receiving a ball valve 42 held against removal by a retainer 43. Below the valve 35 there is an air passage 44 leading from the valve seat out through one side of the rod above the piston.

The cylinder head 40 also has an inwardly opening ball valve 45 pressed upwardly against its seat by a coil spring 47. To facilitate the ready adjustment of the tension 40 of this spring, the valve seat is formed in a collar or bushing 47 screw threaded into a cup 48 against the bottom of which seats the spring. By rotating the collar 47 the 45 valve seat and the spring support may be brought toward or away from each other to increase or decrease the spring tension.

The tube 41 is slidable endwise within the cylinder head and may, if desired, be locked 50 or clamped in the desired adjusted position. A simple form of holding means includes a sleeve 49 integral or rigid with the cylinder head and slotted lengthwise at its upper free end. A nut 50 having a taper thread end 55 gaging this slotted sleeve may be used to slightly collapse the sleeve and clamp the tube with any desired degree of pressure and with the tube in any desired endwise adjustment.

60 My improved device so far as described, operates substantially as follows: The engine piston in reciprocating operates to compress air in the engine base during the explosion stroke of the engine piston and this compressed air may flow through the connection 37 and operate on the under side of the piston 36 to raise the latter together with its rod 38. After the prolongation or upper extension of the rod 38 enters the tube 41 there is no escape for the air above the piston 70 except through the passage 44, the air operating to raise the check valve 42 and escape to the atmosphere through the open end of the piston rod and tube 41. The check valve is prevented from moving from its seat to 75 more than a slight extent by the retainer 43. It will, of course, be obvious that if the cylinder 35 has its axis horizontal rather than vertical or if it be inverted, a spring or suitable means would be used to hold the 80 valve to its seat whereas gravity accomplishes this result when the parts are in the position illustrated. The constriction of the flow of air past the check valve 42 decreases the velocity of the piston until the passage 85 44 comes within and is covered by the tube 41. The piston is then brought to rest as the air above it cannot escape. When the engine piston reaches the upper end of its stroke and the gas pressure in the crank 90 case is released, the piston 36 is held suspended as the air cannot gain access to the air chamber above the piston. As the engine piston starts up on its compression stroke, there is a corresponding rarefaction of the 95 air in the crank case. When this rarefaction is sufficient to overcome the action of the spring 46, holding the check valve 45 to its seat, the said check valve will open and air will enter above the piston 36 and permit 100 the downward movement of the latter. During this downward movement, the upper end of the piston rod extension will come out of the tube 41 or will at least come to such a position that air may enter the cylinder 105 through the tube without passing the check valve 42. The further downward movement of the piston 36 will be very rapid as air may freely enter above the piston and the piston will be drawn down not only by 110 the suction from the crank case but by the action of gravity until the lower end of the piston rod strikes a hammer blow on the upper end of the pump plunger rod. By varying the tension of the spring 46, the air 115 rarefaction necessary to open the valve and permit the start of the downward movement of the piston 36 may be varied at will. Thus the timing of the fuel delivery may be controlled. The tube 41 being adjustable may 120 release the piston for a longer or shorter free stroke and as the length of this stroke will control its force, the blow on the piston rod and the consequent quantity of oil delivered by the force pump may be varied. 125 The piston 36 is shown of dished form so that additional washers may be mounted therein to permit of a variation in the weight of the piston and the consequent force of the blow.

Although the tube 41 may be adjusted by hand to vary the free stroke and the consequent quantity of fuel delivered, I may, if desired, adjust this tube endwise in accordance with the speed of the engine so as to give an automatic governor. By moving the tube inwardly as the speed of the engine increases, the quantity of fuel delivered for each stroke may be correspondingly reduced and the speed held down to the proper limit. Various different means may be provided for effecting this automatic adjustment of the tube 41. Merely as one example of such means, I have shown a jacket water cylinder 52 with a piston 53 therein rigidly secured to a stationary part of the engine. The lower end of the cylinder is connected by a bracket 54 to the upper end of the tube 41 and the lower end of the cylinder is connected by a flexible tube 55 to the outlet of the water circulating pump. The cylinder may have a coil spring 56 between the upper surface thereof and an adjustable cylinder head 57 so as to normally lift the cylinder 52 and pull up the tube to the desired extent for engine idling. The tension of this spring may be varied by rotating the cylinder head 57 and thereby varying the position of the stop for the upper end of the spring. As the engine speed increases, the water pressure in the tube 55 will increase and the pressure in the cylinder 52 will force the latter down against the action of the spring 56 and force the tube 41 into the cylinder 55 to a corresponding extent. Instead of having the hydraulic controlling means operating from the jacket water pump, a centrifugal ball governor or any other governing means may be employed for properly adjusting the position of the tube 41 and the time in the down stroke of the piston 36 when the air will be freely admitted and the pneumatic hammer blow begun.

Various changes, alterations, substitutions, and reversals of parts may be effected without departing from the essential novelty or materially affecting the operation of the device. Other kinds of check valves than those shown may be employed. The upper end of the piston rod may constitute a tube telescoping on the adjustable rod carried by the cylinder head or a weighted diaphragm may be employed instead of the piston or a coil spring may act instead of or together with the gravity in aiding the striking blow of the pneumatic operated member. Other means might be employed for controlling the flow of air to and from the cylinder. In those engines in which the crank case is not used for compression purposes, any other portion of the engine serving this function or a special air compressor operated from the engine may provide the necessary pressure variations for operating the device.

Having thus described my invention, what

I claim as new and desire to secure as Letters Patent is—

1. The combination with an internal combustion engine and a fuel feed pump therefore provided with a reciprocatory plunger, of a cylinder, a free floating piston therein, and pneumatic connections between said engine and said cylinder for effecting the reciprocation of said piston and delivery of hammer blows to said plunger. 75

2. The combination with an internal combustion engine, of an air chamber, a member therein mounted for to-and-fro movement, connections between said chamber and the crank case of the engine for effecting the movement of said member by variations in gas pressure of said case, and a fuel feed pump having a plunger separate from said member and operated by the latter during a portion only of the movement of said member. 80

3. The combination of an internal combustion engine, of a member having a to-and-fro movement effected by gas pressure variations in the engine crank case, a pump 90 having a plunger separate from but in the path of movement of said member, and means for controlling the movement of said member whereby it intermittently delivers hammer blows to said plunger. 95

4. The combination with an internal combustion engine and a fuel feed pump therefore provided with a reciprocatory plunger, a cylinder connected to the crank case of said engine, a free floating piston within 100 said cylinder and adapted to deliver hammer blows to said plunger, and means for controlling the flow of air to and from said cylinder.

5. The combination with an internal combustion engine and a fuel feed pump therefore provided with a reciprocatory plunger, a cylinder having permanently open connections to the crank case of said engine, a free floating piston within said cylinder and 110 adapted to deliver hammer blows to said plunger, and means for controlling the flow of air to and from said cylinder at the side of the piston opposite to said crank case connection. 115

6. The combination with an internal combustion engine and a fuel feed pump therefore provided with a reciprocatory plunger, of an air chamber, a free floating piston therein adapted to operatively engage said plunger, permanently open connections between said chamber and the engine crank case, a valve controlled air outlet at the opposite side of said piston, a valve controlled air inlet, and means for controlling one of said valves. 120

7. A fuel feed pump operating mechanism including a cylinder having one end adapted to be connected to an engine crank case and a spring pressed inwardly operating valve at the opposite end of said cylinder, means for 130

regulating the tension of the spring thereof, and a piston within said cylinder and for operating the fuel feed pump.

8. A fuel feed pump operating mechanism for internal combustion engines including a cylinder, permanently open connections between one end of said cylinder and the crank case, an inwardly opening air valve at the opposite end of said cylinder, and means independent of said valve for freely opening the last mentioned end of the cylinder to the atmosphere when said piston has been moved to a predetermined extent by crank case vacuum.
15. 9. A fuel feed pump operating mechanism including a cylinder, a piston disposed therein, adjustable coöperating means on said cylinder and piston for opening and closing one end of the cylinder to the atmosphere, and an independent valve controlled air inlet to said cylinder on the same side of the piston.

10. The combination with an internal combustion engine, and a reciprocatory fuel feed pump therefor, of a cylinder having one end in open communication with the engine crank case, a piston within said cylinder separate from said pump, and means whereby the movement of said piston in one direction is limited during the compression of air in the crank case and the time of the return movement of said piston under the influence of crank case vacuum for pump operation is controlled.

35. 11. The combination with an internal combustion engine, and a reciprocatory fuel feed pump therefor, of a cylinder having one end in open communication with the engine crank case, a piston within said cylinder, and means whereby the movement of said piston in one direction independent of said pump is limited during the compression of air in the crank case, and the speed and force of the return movement of said piston under the influence of crank case vacuum for pump operation is controlled.

12. The combination with an internal combustion engine, and a reciprocatory feed pump therefor, of a cylinder, a piston therein, connections for moving said piston in one direction upon crank case compression and in the opposite direction by crank case vacuum to operate the pump, and means for timing the release of the piston for said last-mentioned stroke.

55. 13. The combination with an internal combustion engine, and a reciprocatory feed

pump therefor, of a cylinder, a piston therein, connections for moving said piston in one direction upon crank case compression and in the opposite direction by crank case vacuum to operate the pump, and a tube having telescoping relations to said piston and adjustable endwise for timing the release of the piston for said last mentioned stroke.

14. A fuel feed pump operating mechanism for internal combustion engines including a cylinder, a piston movable therein on variations in crank case gas pressure, a projection on said piston, and a tube adjustable lengthwise in respect to said cylinder and telescoping with said projection to control the inflow of air to said cylinder and the release of said piston for free movement under crank case vacuum.

15. The combination of an internal combustion engine and a reciprocal fuel feed pump therefor, of a cylinder and piston communicating with the crank case so that the said piston is moved in one direction upon crank case compression and in the opposite direction upon crank case rarefaction, to operate the pump and means for timing the release of the piston from its air sealed position for said last mentioned stroke.

16. The combination of an internal combustion engine and a reciprocal fuel feed pump therefor, of a cylinder and piston communicating with the crank cases so that the said piston is moved in one direction upon crank case compression and in the opposite direction upon crank case rarefaction to operate the pump, a tube having telescoping relations to said piston and adjustably endwise for regulating the length of the said last mentioned stroke.

17. A fuel feed pump mechanism for internal combustion engines, including a cylinder, a piston movable therein on variations in crank case pressure, a projection on said piston and a tube adjustable lengthwise in respect to said cylinder and telescoping with said projection to control the outflow and inflow of air to said cylinder forming an air seal to hold the piston at rest or to allow the release of said piston for free movement under crank case vacuum.

Signed at Clayton, in the county of Jefferson and State of New York, this 31 day of May, A. D. 1918.

ARTHUR W. THOMPSON.
